(57) **CLAIM**

The ornamental design for a hummingbird feeder reservoir,
as shown and described.

DESCRIPTION

FIG. 1 is a top front perspective view of a hummingbird
feeder reservoir showing our new design, the broken lines in
the drawings representing environment which forms no part
of the claimed design.

FIG. 2 is a left side elevational view of the hummingbird
feeder reservoir illustrated in FIG. 1.

FIG. 3 is a top plan view of the hummingbird feeder
reservoir illustrated in FIG. 1.

FIG. 4 is a right side elevational view of the hummingbird
feeder reservoir illustrated in FIG. 1.

FIG. 5 is a bottom plan view of the hummingbird feeder
reservoir illustrated in FIG. 1.

FIG. 6 is a left side elevational view on a reduced scale of
the humming bird feeder reservoir illustrated in FIG. 1; and,
FIG. 7 is a top front perspective view on a reduced scale of
the humming bird feeder reservoir illustrated in FIG. 1.
